UNITED STATES PATENT OFFICE.

ALVIE C. CRIMMEL, OF HARTFORD CITY, INDIANA.

DISPENSING DISPLAY STAND.

Application filed February 23, 1923. Serial No. 256,088.

This invention relates to a display stand for a vending container.

The chief object of the invention is to provide a stand for a container adapted to contain a liquid to be dispensed, which stand includes a dispensing nozzle and a chamber to receive the liquid from the container.

The chief feature of the invention consists in the formation of the stand in two parts and the detachable association therebetween, both parts being made of glass or other suitable vitreous material and adapted for the reception of display or advertising matter, if and when desired.

One feature of the invention consists in the accomplishment of the foregoing object, and another feature of the invention consists in the formation of the stand such that it is adapted to simultaneously support a plurality of liquid containers having different liquids to be dispensed therefrom.

The full nature of the invention will be understood from the accompanying drawings and the following description and claims:

In the drawings Fig. 1 is a central sectional view of a multiple standard and dispensing device with parts in detail. Fig. 2 is a top plan view of the standard proper with the 30 globes or containers removed therefrom, the section line 1-1 indicating the section in which Fig. 1 is taken.

In the drawings 10 indicates a globe or container having the neck or throat 11 and a standard 12 at its upper end includes an annular seat 13 defined by a flange 14 for supporting said globe or container. A gasket or washer 15 is provided if and when desired. The globe 10 may be suitably colored and provided with any type of ornamentation that it is desired to disclose, and said globes are of the standard type now in commercial use. The standard 12 includes a liquid-containing chamber 16 having an outlet 17 and mounted in said outlet 17 is a dispensing nozzle 18 of the usual or preferred character. Herein the exterior of the standard is ornamented by corrugations as at 19 but the same may be otherwise formed for receiving suitable advertising or display matter, and said standard furthermore may be made of glass or other vitreous material of any desired color to match the globe or container 10. The tubular standard 12 is closed by the plate or base portion 20 having a flat face 21, and herein depending from said flat face and

centrally thereof is a projection 22 having a threaded exterior 23.

The base consists of a hollow outwardly and downwardly inclined body portion 24 having a base supporting flange 25, and a top face portion 26 having the face 27 adapted to engage face 21 of the standard. The top 26 is apertured as at 28 and the threaded projection 22 extends into said aperture with 65 a slight clearance.

A retaining member includes the plate 29 adapted to engage the under-face 30 of the top portion of the base and extending from one face of said plate 29 is a threaded tubular portion 31 adapted for threaded engagement with the threaded projection 22. A finger piece 32 of suitable conformation is secured to the opposite face of the plate portion 29 so that the clamping and anchoring 75 member can be threaded on to the threaded projection and bear upon the apertured face member.

As shown clearly in both figures, the base 24 is multiple in character and adapted to support a plurality of standards, and herein two in number, and each standard in turn supports a liquid container or globe and each dispenses a liquid of suitable character. Herein the multiple standard is so arranged 85 that each end is semi-circular in horizontal section and the ends are connected by tangential walls. If desired, each wall, and preferably the interior thereof, is recessed as at 33 to provide a pocket adapted to receive advertising or display matter, it being understood that in this event the base is formed of transparent or semi-translucent material. If desired, pocket 33 may be positioned upon the exterior surface of the base 90 if and when that said base is opaque or semi-opaque in character, and then said pocket would receive upon the exterior of the base suitable advertising or display matter. It will also be apparent that each of the standards 12 might be of different color from each other and from the base, or the standard might differ from the base in color, thus permitting contrasting color arrangements.

One of the advantages of having the 105 standard 12 of glass is that it is sanitary and can also be readily cleaned but will not have any corrosive action upon the contents in the chamber 16. If the standard and base were formed integral the resultant loss by 110 reason of breakage, warpage, shrinkage, crackling and cracking would be enormous.

An attempt to make a multiple base is practically impossible not only by reason of the cost of the mold construction, but also by reason of the unequal cooling strains included 5 etc. previously set forth.

The present construction, therefore, in addition to having the advantage of providing possible color variation also permits the standard to be made separate from the base 10 and thus reduces the mold cost, and since the parts are relatively small and are substantially uniform in outline, they readily lend themselves to molding and quantity production with a minimum amount of loss 15 by reason of the aforesaid conditions. While a multiple base is shown herein, a single base may be employed.

The invention claimed is:

1. In combination with a container adapted to contain liquid to be dispensed, a hollow base having an upper face including an aperture therethrough, a tubular standard having a container supporting portion adjacent its upper end and a base supported portion at 25 its opposite end, a peripherally threaded projection on said base supported portion and receivable by said aperture, and threaded means engaging said threaded projection and the base for clampingly securing the 30 standard and base in unitary arrangement.
2. In combination with a container adapted to contain a liquid to be dispensed, a hollow base having an upper face, a tubular

standard having a container supporting portion adjacent its upper end and a supporting 35 face at its lower end, one of said faces including an aperture extending therethrough, a threaded projection on the non-apertured face and projecting into said aperture when said standard and base are in superposed 40 relation, and threaded means bearing on the apertured face portion and engaging the threaded projection for clampingly securing the standard and base in unitary arrangement. 45

3. In combination with a plurality of similar containers, each adapted to contain a liquid to be dispensed, a hollow base having an upper supporting face portion for each container, a tubular standard for each container and supporting the same at the upper end and including a base face engaging face portion, one of each pair of engaging face portions including an aperture extending therethrough, a threaded projection on the 50 non-apertured face portion of each pair of said engaging pair of face portions and projecting into the adjacent aperture, and threaded means for each projection engaging the adjacent apertured face portion for 55 clampingly uniting each standard to the common base in unitary arrangement. 60

In witness whereof, I have hereunto affixed my signature.

ALVIE C. CRIMMEL
